CLAIM

The ornamental design for a pet bowl latch, as shown and described.

DESCRIPTION

FIG. 1 is a perspective view of a pet bowl latch, showing my new design.

FIG. 2 is an opposing perspective view thereof.

FIG. 3 is a back view thereof.

FIG. 4 is a side view thereof, the opposite side being a mirror image thereof.

FIG. 5 is a top view thereof.

FIG. 6 is a bottom view thereof.

FIG. 7 is a side view thereof, with the latch in an unlatched state.

FIG. 8 is another perspective view of the pet bowl latch disposed in an environment in which it is used; and, FIG. 9 is a further perspective view of the pet bowl latch disposed in the environment in which it is used.

The dash-dash broken lines illustrate portions of the article and environmental subject matter that form no part of the claimed design, and the dot-dash broken lines define the bounds of the claimed design and form no part thereof.
